CLAIM

The ornamental design for a retaining wall block, as shown and described.

DESCRIPTION

FIG. 1 is a front perspective view of a retaining wall block. FIG. 2 is a rear perspective view of the retaining wall block of FIG. 1.

FIG. 3 is a front view of the retaining wall block of FIG. 1. FIG. 4 is a rear view of the retaining wall block of FIG. 1. FIG. 5 is a right side view of the retaining wall block of FIG. 1.

FIG. 6 is a left side view of the retaining wall block of FIG. 1.

FIG. 7 is a top view of the retaining wall block of FIG. 1. FIG. 8 is a bottom view of the retaining wall block of FIG. 1; and,

FIG. 9 is a cross-sectional view through a center of the retaining wall block taken along line 9-9 in the block of FIG. 3.

Broken lines are shown for the purpose of environmental structure and form no part of the claimed design. Cross-hatching lines are shown in FIG. 9 for the purpose of identifying the location of internal structure and form no part of the claimed design.

1 Claim, 9 Drawing Sheets
